UNITED STATES PATENT OFFICE.

HARRY J. VORTRIEDE, OF TOLEDO, OHIO.

BLOTTER PAD.

Application filed April 7, 1928. Serial No. 268,211.

This invention relates to stationery, but more particularly to blotters, and an object of the invention is to provide a simple and efficient blotter having renewable features, 5 so that when the blotting surface is used, a new surface can be presented for use by severing the used surface from the remainder.

Another object of the invention is to provide a new and improved blotter pad having 10 the unique features of construction herein-after described.

The invention is shown by way of illustration in the accompanying drawings, in which:

Fig. 1 is a top plan view of the blotter pad; 15 Fig. 2 is a side edge view of the blotter pad; and

Fig. 3 is an end edge view of the blotter pad.

The illustrated embodiment of the invention comprises a blotter pad which is shaped 20 in the form of a bottle, and consists of a relatively stiff cover sheet 1, on which suitable advertising indicia or inscriptions may be displayed, and a plurality of blotting sheets 25 2, the edges of which are co-incident, and together form a unitary structure.

The blotting sheets are held together, and the cover sheet 1 is held to the blotting sheets by adhesive 3, which covers all the side edges 30 of the blotter pad except the front edge 4, which in this instance, forms the extreme end of the bottle neck. No adhesive is applied to this edge portion, and the sheets are free to flex relatively to each other.

35 In use, after the lowermost blotting sheet 2 has been used, it is merely necessary to insert a knife or other tool to separate the lowermost blotting sheet from the adjacent superposed sheet, and sever that sheet from the 40 pad, thereby presenting a new blotting surface. In this manner it is evident that the blotting pad may be used for a considerable period of time, and a handy and convenient blotter is provided. The necks of the sheets 45 it will be noted present relatively narrow portions which project outwardly from the top edges of the blotting sheets, the outer end edges of which portions are free of connec-

tion and afford thumb-engaging means so that by flexing all of the sheets, except the 50 one to be removed, in a direction toward the cover sheet, removal of said one sheet is readily accomplished and can in fact be accomplished by tearing and without the use of a 55 knife.

It is proposed to color the adhesive 3 differently from the blotting sheets, so as to present an attractive appearance. The adhesive 3 forms a covering for the side edges of the pad, as indicated, and reinforces the same to 60 prevent tearing.

In order to enable the individual blotters to be readily separated from each other, adjacent blotters are differently colored. For example, the lowermost blotter may be colored 65 red and the next superposed blotting sheet colored green, thereby enabling the sheets to be conveniently distinguished from each other and facilitating separation.

While I have shown and described a construction which is the best form known to me at the present time, it is understood that numerous changes in details of construction and operation may be effected without departing from the spirit of the invention, especially 75 as defined in the appended claim.

What I claim is:

A blotting pad composed of a cover and a series of superimposed blotting sheets, the side and bottom edges of the sheets and cover 80 being connected by lines of adhesive, the top edges of the sheets being free of connection with one another, said cover and sheets having registering relatively narrow portions 85 which project outwardly from the top edges of the cover and sheets, the outer end edges of which portions are free of connection and afford thumb engaging means, so that by flexing of all of the sheets, except the one to be removed, in the direction toward the cover 90 sheet, to thereby separate and enable removal of said one sheet from the remaining sheets.

In testimony wherof I have hereunto signed my name to this specification.

HARRY J. VORTRIEDE.
